(57)

CLAIM

The ornamental design for a drill, as shown and described.

DESCRIPTION

FIG. 1 is a perspective view of the a drill.

FIG. 2 is a front view of the handle.

FIG. 3 is a rear view of. the handle

FIG. 4 is a left view of the handle.

FIG. 5 is a right view of the handle.

FIG. 6 is a top view of the handle; and,

FIG. 7 is a bottom view of the handle.

The broken line showing of Structural Features is included for the purpose of illustrating Non-Claimed Subject Matter and forms no part of the claimed design.

1 Claim, 5 Drawing Sheets
